UNITED STATES PATENT OFFICE.

GEORGE M. PAINTER, OF CHICAGO, ILLINOIS.

ELECTRICALLY-OPERATED HAMMER.

1,276,104.

Specification of Letters Patent. Patented Aug. 20, 1918.

Application filed January 2, 1917. Serial No. 140,055.

To all whom it may concern:

Be it known that I, GEORGE M. PAINTER, a citizen of the United States, and a resident of Chicago, in the county of Cook and State 5 of Illinois, have invented certain new and useful Improvements in Electrically-Operated Hammers; and I do hereby declare that the following is a full, clear, and exact description thereof, reference being had to the 10 accompanying drawings, and to the letters of reference marked thereon, which form a part of this specification.

This invention relates to improvements in electric hammers and consists of the matters hereinafter described and more particularly pointed out in the appended claims.

The object of the invention is to provide a hammer, such as and somewhat in the form of the well known pneumatic hammer, 20 which may be operated by an electric current in an efficient and economical manner. The advantages of my invention will appear as I proceed with my specification.

In the drawings:

25 Figure 1 represents a side elevation of my improved hammer.

Fig. 2 represents a longitudinal, central section through the hammer.

Figs. 3, 4 and 5 represent transverse sectional views of the hammer, in planes indicated respectively by the lines 3—3, 4—4 and 5—5 of Fig. 2.

Fig. 6 represents on an enlarged scale a side elevation of a switch device used in the 35 hammer.

Fig. 7 represents on a similar scale a longitudinal section through the reciprocating hammer member.

Fig. 8 represents a side elevation and part 40 sectional view of one of the commutator bars used in the hammer.

Fig. 9 represents a side elevation of one of the conductor bars or rods used in the hammer.

45 Fig. 10 represents diagrammatically the electric wiring of the hammer.

Fig. 11 is a detail perspective view illustrating the relation of the switch member conductor bars and commutator bars.

50 Referring now to that embodiment of my invention illustrated in the accompanying drawings:

12 indicates the body of the tool or hammer. Said body is in the form of an

elongated tube or barrel 13 provided at one 55 end with a closed head 14 and at the other end with a tool-holder retaining cap 15. Both the head 14 and the cap 15 are screwed upon the ends of the barrel and the cap provides bearing and support for a tool-holder 60 16 as in the case of a pneumatic hammer. Within the barrel is fixed an insulating tube 17 of fiber or like material which fits snugly against the inner wall of said barrel.

The barrel 13 is divided longitudinally 65 into two chambers, substantially equal in length,—that is to say, a solenoid chamber 18 and a commutator chamber 19. 20 indicates a rod, which as shown is tubular, and which extends the length of the barrel and 70 is placed in the longitudinal central axis thereof. Said rod provides a bearing for a longitudinally reciprocating member 21 which is the core of the solenoids presently to be described and for a longitudinally 75 reciprocating commutator or brush carrying member 22 associated with said core.

23 indicates a plurality of separate coils or solenoids which are arranged end to end in succession in the solenoid chamber 18 80 with their common axis coincident with the longitudinal central axis of the barrel 13, and with the axis of the core 21 which is slidably mounted on the rod 20. The solenoids are formed to provide a plurality of 85 flat rings (see Figs. 2 and 3) and are held in place, as shown by means of apertured end plates or disks 24, 25 and by three longitudinally extending rods 26^a, which are spaced at equal angles about and in engagement 90 with the peripheries of said solenoid rings and connect said end plates 24, 25 together. Suitable insulating washers 23^a, 23^b are interposed between the end coils of the sole- 95 noid 23 and the said end plates 24, 25. (See Fig. 2). The end plates or disks 24, 25 bear within the insulation sleeve 17 and the disk 24 has a tubular flange 24^a which has thrust bearing against the cap 15.

The core 21 is fixed on a tube 26 which 100 has longitudinal, sliding bearing upon the rod 20 and which extends into the commutator or switch chamber 19. Said core is placed between a fixed collar or flange 26^a on the tube 26 and a collar 26^b screwed upon 105 the end of said tube. The core is preferably laminated longitudinally and comprises a plurality of radial, longitudinally extending

bars 21^a held between flanged end rings 21^b, 21^c. (See Fig. 7.)

The commutator 22 is slidably mounted on the tube 26 between two collars 27, 28 fixed to said tube and spaced apart a distance greater than the length of the commutator. Said commutator has a body made of an insulating block 30 fixed on a sleeve 31 that provides its bearing upon the tube 26. Associated with the commutator are a pair of laterally spaced, longitudinally extending commutator bars 32, 32 (see Figs. 2 and 4) and a pair of conductor bars 33, 33. 34, 34 and 35, 35 indicate grooved metal conducting rollers which are arranged in longitudinally spaced pairs upon the block 30 and which engage said commutator bars. 36, 36^a and 37, 37^a indicate grooved metal rollers which are likewise arranged in longitudinally spaced pairs upon said block 30 and which engage the conductor rods 33. The several sets of rollers provide the brushes for the commutator. The rollers 34, 34, and 35, 35 are mounted respectively on spring controlled arms 34^a, 35^a pivotally carried upon metal rods 34^b, 35^b which extend transversely through the block 30 and provide electrical connection between the rollers of each pair. The rollers 36, 36^a and 37, 37^a are carried on spring controlled arms 36^b, 36^b and 37^b, 37^b which are pivoted to the sides of the block 30. The roller 37^a is electrically connected to the rollers 35, 35 in any convenient manner (see Fig. 11) and the roller 36 is electrically connected to the rollers 34, 34.

The commutator bars 32, 32 and the conductor bars 33, 33 are supported by means of apertured plates or disks 38, 39, the one 38 being arranged adjacent to the previously mentioned solenoid retaining plate 25 and the other 39, being placed close to the head 14 of the barrel. The two disks 25 and 38 are provided with inter-engaging short sleeves 25^x, 38^x, respectively which are insulated from each other by means of a collar 40 made of fiber or other suitable insulating material.

The commutator bars 32, 32 each consists of a plurality of insulated conductor rings 41 corresponding in number to the number of solenoids in the solenoid chamber (see Fig. 8), of two extra rings 42, 42 placed one at each end of the commutator bar; and of a rod 43, on which said rings are mounted and which extends through suitable apertures in the plates 38, 39. The rod 43 is retained in place by means of nuts 43^a, 43^a. The conductor rings on the rod are insulated in any convenient manner from the rod as by means of a sleeve 44 and from each other by means of insulating rings 45. Suitable insulation collars are also provided at the ends of the rod to insulate them from the plates 38, 39.

The conductor bars 33, 33 consist of rods which extend through apertures in the plates 38, 39 (see Fig. 9), and are suitably insulated from said plates in any familiar manner. Each rod has a head 33^x at one end 70 which engages the disk 38 and a nut 33^y at the other end. Thus the rods of the commutator bars and the conductor bars act to retain the plates 38, 39 in proper spaced relation. One of the rods 33 extends through 75 the head 14 from which it is insulated in any convenient manner.

A spring controlled push button 48 is mounted upon the end of this rod with its head located beyond the head of the barrel 80 in position to be actuated by a spring controlled arm 47 carried by the usual handle 14^a fixed to the head 14 of the barrel. A contact 33^z connected to the rod 33 is adapted to be engaged by contact 48^a when the 85 push button 48 is pushed home. (See Fig. 9.)

The other rod 33 is permanently connected to one of the line wires leading from the source of electric supply, while the other 90 line wire is connected to the push button 48. Thus it is manifest that when the arm 47 is operated, the conductor bars 33, 33 will be supplied with current.

The several solenoid coils are connected 95 in series (see Fig. 10) by means of bridge pieces 23^x and the bridge-pieces themselves are connected in succession by conductor wires to the rings of the two commutator bars in pairs, the opposite rings on the two 100 commutator bars constituting a pair. (See Fig. 11.) For convenience in following the circuits, the rings of the commutator bars, except the end rings 42, 42, have been numbered in pairs in succession from 1 to 31 and the solenoid coils have been numbered in like manner. The first solenoid coil is connected to the rear end rings 42 of the 105 commutator bars. The bridge piece 23^x between the solenoids 1 and 2 is connected to the commutator rings 1 on the two commutator bars. The bridge piece between the solenoids 2 and 3 is connected to the commutator rings 2 on the commutator bars, and so on. The forward end rings on the 110 commutator bars are not in any circuit and are dead.

From the foregoing description it will be apparent that when the commutator 22 is in any position in its compartment (as for example in the position illustrated diagrammatically in Fig. 10), the electrical connection will be as follows: from the conductor rod 33 to the roller 37^a, to the rollers 35, thence to the commutator rings 41 of the two commutator bars, with which said rollers 35 are in contact,—in this case the contact rings numbered 18 in the series; and thence to the bridge piece 23^x connecting the solenoids numbered 18 and 19 of the 115 120 125 130

solenoid series. The only path for the current back to the commutator is through commutator rings 41 with which the rollers 34, 34 are in contact. In the example illustrated, these are the rings numbered 26 in the series. As these rings are connected to the bridge piece connecting the solenoids numbered 26 and 27 in the series, and as the solenoids between said last named bridge piece and the one first mentioned, namely that connecting the solenoids 18 and 19 are all connected in series, it is apparent that all of the solenoids numbered 19 to 26 are included in the circuit. From the rollers 34 of the commutator, the current will pass to the roller 36 and thence to the second conductor rod 33.

Manifestly, when the commutator is moved in either direction, it will act to connect in the circuit the solenoids in advance of it, in succession in the direction in which it is moving, and will at the same time cut out of circuit the solenoids at the rear in succession in the same direction.

The commutator 20, being mounted as heretofore stated on the tube 26, to which the core 21 is fixed, manifestly moves with said core. As pointed out, however, the commutator is slidably mounted on the bearing tube 26 between the shoulders 27 and 28, and a sliding or shifting movement of the commutator on said tube, occurs as the commutator approaches the limits of its endwise travel in its associated chamber 19. The means for imparting such shifting movement to the commutator is as follows:— Secured in any suitable manner to the under side of the block 30 on its longitudinal median line is a yielding latch bar 50 which extends at both ends beyond the ends of the commutator block 30. The ends of said latch bar are formed to provide upright shoulders 51, 51 and downwardly and outwardly inclined yielding abutments 52, 52, which are arranged in line with and which are adapted to engage lugs or tripping members 53, 53 fixed to the disks 38, 39. The shoulders 51, 51 are adapted to engage with either of the collars 27, 28 in the tube 26, and to lock the commutator as a whole to that collar, toward which the said commutator has been last moved, and thus fix it at one of the other ends of its movement on its bearing tube 26.

In the top of the commutator block 30 is formed a longitudinally extending bore 55 which is closed at its ends by means of bushings 56, 56. Said bushings provide sliding bearing for plungers 57, 57 each of which have a head within the bore 55 and which project beyond the ends of the commutator block. Abutment lugs 60 are fixed to the disks 38, 39 in line with the plungers and are adapted to be engaged by said plungers when the commutator reaches either end of

its path of travel. A coiled expansion spring 58 is placed in the bore 55, between the heads of the plungers 57.

The commutator is normally locked to its bearing tube 26 at one end or the other of said tube and particularly at that end of the tube faced in the direction in which the commutator is traveling, as illustrated in Fig. 2, wherein the commutator is shown as moving toward the disk 38. As said commutator approaches the disk 38, the yielding abutment 52 at the approaching end of the commutator, will engage the trip member 53 on the disk 38 and will be forced downwardly so as to release its associated shoulder 51 from its engagement with the collar 27 on the bearing sleeve 26. The plungers 57 project somewhat in advance of the yielding abutments 52 and are adapted to engage the lugs 60 before the yielding abutments 52 effectively engage the tripping members 53. Thus, before the yielding abutment 52 is actuated as above described, the associated plunger 57 will have engaged its lug 60, and, as the commutator continues to move in the same direction, will be forced by said fixed lug to move in the bore 55 and compress the spring 58. When the shoulder 51 has been released from the collar 27, the spring 58 will expand back and as the plunger 57 is still in engagement with the fixed lug 60, this expansion will act against the opposite plunger 27 and act to shift or kick the commutator block 30 to the other end of the tube 26, where the shoulder 51 at that end will snap into locking engagement with the collar 28.

The parts are designed, as shown in the drawings, so that the kick produced by the spring 58 at the end of the movement of the commutator will act to move the commutator block 30 upon its bearing sleeve 26, a distance equal approximately to the space on the commutator bars occupied by three of the commutator rings. Thus, assuming the core 21 and the commutator to be moving toward the rear end of the barrel, as illustrated in Fig. 2, when the yielding abutment 52 strikes the associated trip lug 53 on the disk 38 and the plunger rod 57 strikes the fixed lug 60 thereon, as explained, somewhat in advance of the action of the other parts, the commutator block will be immediately shifted to the other end of the sleeve 26 and thus bring the contact rollers or brushes 34 and 35 respectively into contact with commutator rings, which are three removed in the direction opposite to that in which the commutator has been moving from the rings with which they were in contact at the time the abutment and plunger rod struck their associated fixed parts. This, as will appear, provides for the reversal of the movement of the core which constitutes the hammer.

The operation of the improved electric hammer will be apparent from the description already given. The commutator 22, as has already been pointed out, normally moves with the core 21 of the solenoid, but is capable of a small independent movement which is brought about at the end of its path of travel in either direction. At any time when the circuit of the lead wires to the hammer is closed, the particular solenoids 23 included in the series connected by the commutator at the time, will act to draw the hammer or solenoid toward the center of magnetism. This will cause the commutator moving with the core, by bringing in new solenoids in advance of the movement of the core and cutting out those in the rear, to advance the center of magnetism, thereby producing a continuous and rapid advance of the movement of the core in that direction. As the core or hammer approaches the front end of the barrel and its striking position against the tool holder 16, and in fact just as it reaches this point, the commutator will be actuated by means of the yielding abutment 52 and the plunger rod 57 at the forward end of the commutator to release the commutator from its rigid connection with the tube 26 to which the core is attached and to kick the commutator over several rings of the commutator bar to its rearward position. This will immediately remove the center of magnetism from that position where it has been drawing the core or hammer head toward the tool holder 16, to a position removed forwardly therefrom, so as to exert a pulling movement on the core in a direction toward the rear of the hammer. The core will thereupon immediately move toward the hammer head, carrying the commutator with it, and reversing the travel of the field toward the hammer head instead of causing it to travel toward the tool holder, as above described.

Apparently, when the commutator reaches the handle end of the tool casing, the action with respect to the commutator will be reversed, and the field will be again shifted toward the tool holder with the resulting movement of the core toward the same. Thus, the required reciprocation to actuate the core as a hammer in the way of the ordinary pneumatic hammer will be produced.

In the construction of the hammer, the tool holder is extended into the bore of the solenoids, such a distance that the core or hammer will strike the tool holder at substantially the same time that the commutator has its movement with the core reversed. This results in delivering the full force of the blow due to the draw of the magnetic field against the tool head.

In order to prevent any pneumatic cushion being formed at the end of the travel of the hammer, the tool head is provided

with a passageway (as indicated in Fig. 2) to permit the escape of air that travels in advance of the hammer. Upon the return stroke it is apparent that the shifting center of the field caused by the shifting of the commutator with reference to the core, will provide a magnetic cushion which will ease up and break to reduce the force of the blow of the hammer when it reaches the end of its stroke when traveling toward the handle end of the barrel.

While in describing my invention, I have referred to many details of mechanical and electrical construction and arrangement, it is manifest that my invention is capable of various modifications in that respect and it is to be understood that it is in no way to be limited thereto except as may be pointed out in the appended claims.

I claim as my invention:

1. An electro-magnetic motor comprising a plurality of solenoids arranged in longitudinal succession with a common longitudinal axis and connected in series, a core constituting a hammer, movable in the common longitudinal axis of said solenoids, a commutator bar provided with a plurality of commutator rings, each ring being connected to one of said solenoids, a commutator block normally movable with said core, but capable of a limited, independent movement, said commutator block having brushes engaging the commutator rings associated with the solenoids, and positive means for shifting said commutator at the ends of the path of travel of said core, to shift the magnetic field of said solenoids to a point in the reverse direction from that in which said core has been traveling.

2. An electro-magnetic motor comprising a plurality of annular solenoids arranged in longitudinal succession with a common longitudinal axis and connected together in series, a core having an extension member, reciprocable in the common longitudinal axis of said solenoids, a commutator bar comprising a plurality of commutator members, each of which is connected to one of said solenoids, a commutator block carried by said core extension, but capable of a limited, independent movement thereon, said commutator block having brushes engaging the commutator members associated with the solenoids, and positive means for shifting said commutator block on said core extension at the ends of the path of travel of said core, to shift the magnetic field of said solenoids to a point in the reverse direction from that in which the core has been traveling.

3. An electro-magnetic motor comprising a plurality of annular solenoids arranged in longitudinal succession with a common longitudinal axis and connected together in series, a core having an extension member,

- reciprocable in the common longitudinal axis of said solenoids, a commutator bar comprising a plurality of commutator members, each of which is connected to one of 5 said solenoids, a commutator block carried by said core extension, but capable of a limited, independent movement thereon, said commutator block having brushes engaging the commutator members associated with the 10 solenoids, means locking the said commutator block to said core extension at the limit of its movement on said extension, and means releasing said block from its locked position on said extension at the ends 15 of the path of travel of said core, to shift the magnetic field of said solenoids to a point in the reverse direction from that in which the core has been traveling. 70
4. An electro-magnetic motor comprising 20 a plurality of annular solenoids arranged in longitudinal succession with a common longitudinal axis and connected together in series, a core having an extension member, reciprocable in the common longitudinal 25 axis of said solenoids, a commutator bar comprising a plurality of commutator members, each of which is connected to one of said solenoids, a commutator block carried by said core extension, but capable of a limited, independent movement thereon, said 30 commutator block having brushes engaging the commutator members associated with the solenoids, means automatically locking the said commutator block to said core extension at the limit of its movement on said 35 extension, means releasing said automatic locking means of said block on said core extension as the core approaches the ends of its movement, and means for shifting said block at the ends of the path of travel of said core, to shift the magnetic field of said solenoids to a point in the reverse direction from that in which the core has been traveling. 80
5. An electro-magnetic motor comprising 40 a plurality of annular solenoids arranged in longitudinal succession with a common longitudinal axis and connected together in series, a core having an extension member, reciprocable in the common longitudinal 45 axis of said solenoids, a pair of commutator bars, each comprising a plurality of commutator members, the commutator members on one bar being connected to an associated 50 member on the other bar to form pairs of commutator members, each pair of said commutator members being connected to one of said solenoids, current conductor rods spaced from said commutator bars, a com- 55 mutator block carried by said core extension, but capable of a limited, independent movement thereon, said commutator block having rotative brush members engaging upon said commutator bars and said conductor rods, 60 and yielding means for shifting said com- 65 mutator block on said core extension at the ends of the path of travel of said core, to shift the magnetic field of said solenoids to a point in the reverse direction from that in which the core has been traveling. 75
6. An electro-magnetic motor comprising 70 a casing, means dividing said casing into a plurality of compartments, a plurality of annular solenoids arranged in longitudinal succession in one of said compartments, said 75 solenoids being connected together in series, a supporting member arranged in said casing in the longitudinal axis of said solenoids, a core having an extension member, slidably arranged on said supporting member, spaced 80 commutator bars in the other of said compartments, said commutator bars comprising commutator members arranged in pairs, each pair being connected to one of said solenoids, a commutator block mounted on that 85 end of said core extension normally located in said second mentioned compartment, and capable of a limited, independent movement on said core extension, brushes on said commutator block connecting the members of 90 each pair of commutator members together, and means for shifting the commutator block on said core extension at the ends of the path of travel of said core on said supporting member, to shift the magnetic field 95 of said solenoids to a point in the reverse direction from that in which the core has been traveling. 100
7. An electro-magnetic motor comprising 105 a casing, means dividing said casing into a plurality of compartments, a plurality of annular solenoids arranged in longitudinal succession in one of said compartments, said solenoids being connected together in series, a supporting member arranged in said casing in the longitudinal axis of said solenoids, a core having an extension member slidably arranged on said supporting member, spaced 110 commutator bars comprising commutator members arranged in pairs, each pair being connected to one of said solenoids, conductor rods also arranged in said last-mentioned compartment, a commutator block mounted in said core extension but capable of a limited, independent movement there- 115 on, brushes on said commutator block engaging upon said commutator bars and on said conductor rods, and means for shifting the commutator block on said core extension at the end of the path of travel of the core on 120 said supporting member, to shift the magnetic field of said solenoids to a point in the reverse direction from that in which the core has been traveling. 125
8. An electro-magnetic motor comprising 130 a casing having front and rear end walls, and an intermediate wall dividing said casing into two compartments, a plurality of annular solenoids arranged in longitudinal succession in one of said compartments, said

- solenoids being connected together in series, a supporting member extending substantially the full length of the casing in the longitudinal axis of said solenoids, a tube 5 slidably mounted on said supporting member, a core fixed to the front end of said tube and associated with said solenoids, spaced bars in the other of said compartments, fixed at their ends in said intermediate 10 wall and said rear end wall, commutator members arranged in pairs on said spaced bars, each pair being connected to one of said solenoids, conductor rods in said commutator compartment and fixed at their ends in 15 said intermediate wall and said rear end wall of the casing, a commutator block mounted on the rear end of said tube but capable of a limited, independent movement thereon, rotative brushes on said commutator block 20 engaging upon said commutator members on said bars and upon said conductor rods, and means for shifting the commutator block on said tube at the ends of the path of travel of said core on said supporting member to 25 shift the magnetic field of the solenoids to a point in the reverse direction from that in which the core has been traveling.
9. An electro-magnetic motor comprising a casing having front and rear end walls, 30 and an intermediate wall dividing said casing into two compartments, a plurality of annular solenoids arranged in longitudinal succession in one of said compartments, said solenoids being connected together in series, 35 a supporting member extending substantially the full length of the casing in the longitudinal axis of said solenoids, a tube slidably mounted on said supporting member, a core fixed to the front end of said 40 tube and associated with said solenoids, spaced bars in the other of said compartments, fixed at their ends in said intermediate wall and said rear end wall of the casing, a commutator block 45 mounted on the rear end of said tube, but capable of a limited, independent movement thereon, rotative brushes on said commutator block 50 engaged upon said commutator members on said bars and upon said conductor rods, means locking said commutator block on said tube at the limit of its movement thereon, means releasing said block from its locked position on said tube at 55 the other end of the path of travel of said core, and means for shifting the commutator block on said tube after it has been unlocked, to shift the magnetic field of said solenoids to a point in the reverse direction from that 60 in which said core has been traveling.
10. An electro-magnetic motor comprising a casing having front and rear end walls, 65 and an intermediate wall dividing said casing into two compartments, a plurality of annular solenoids arranged in longitudinal succession in one of said compartments, said solenoids being connected together in series, 70 a supporting member extending substantially the full length of the casing in the longitudinal axis of said solenoids, a tube slidably mounted on said supporting member, a core fixed to the front end of said tube and associated with said solenoids, spaced bars in the other of said compartments, fixed at their ends in said intermediate 75 wall and said rear end wall, commutator members arranged in pairs on said spaced bars, each pair being connected to one of said solenoids, conductor rods in said commutator compartment and fixed at their 80 ends in said intermediate wall and said rear end wall of the casing, a commutator block mounted on the rear end of said tube, but capable of a limited, independent movement thereon, rotative brushes on said commutator block 85 engaging upon said commutator members on said bars and upon said conductor rods, means locking said commutator block on said tube at the limit of its movement thereon, means releasing said block from its locked position on said tube at 90 the other end of the path of travel of said core, and means for shifting the commutator block on said tube after it has been unlocked, to shift the magnetic field of said solenoids to a point in the reverse direction from that 95 in which said core has been traveling.

In testimony that I claim the foregoing as my invention I affix my signature in the presence of two witnesses, this 28th day of December A. D. 1916.

GEORGE M. PAINTER.
